BALANCER FOR LADDERS

Henry Schwarz and Charles A. Eilers, Montague,
Mich.

Application May 29, 1939, Serial No. 276,434

1 Claim. (Cl. 228—67)

This invention relates to balancers for ladders and has for an object to provide an extension attachment for ladders whereby the user can stand on the top rung of the ladder and grasp the extension to balance himself while working.

A further object is to provide a ladder of this type having a wall rest to permit the user working behind a ladder, the wall rest being adapted to space the top of the ladder about 10" from a wall, the weight of the balancer firmly locking the extension attachment against accidental collapse.

A further object is to provide a ladder having a balancer and wall rest adapted to be folded back along the ladder when not in use so as to occupy minimum space.

A further object is to provide a device of this character which will be formed of a few strong, simple and durable parts, which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

30 In the accompanying drawing forming part of this specification,

Figure 1 is a perspective view of a ladder equipped with a balancer attachment and a wall rest in accordance with the invention.

35 Figure 2 is a detail sectional view, drawn to enlarged scale, of the upper portion of the ladder shown in Figure 1.

Figure 3 is a detail front elevation, drawn to enlarged scale, showing the pivotal connections 40 of the balancer attachment and wall rest with the ladder.

Figure 4 is a detail cross sectional view taken on the lines 4—4 of Figure 2.

45 Figure 5 is a detail perspective view of the wall rest.

Referring now to the drawing in which like characters of reference designate similar parts in the various views, a conventional ladder is shown comprising side rails 10 and rungs 11. In carrying out the invention a balancer attachment is pivotally secured to the top of the ladder to extend upwardly there beyond. The attachment comprises an inverted U-shaped frame 12 having a pair of rungs 13. The lower ends of the sides 50 of the frame are offset inwardly as shown at 14

in Figure 3 and are pivotally attached to the rails of the ladder above the uppermost rung 11, through the medium of pivot bolts 15. A spacer 16 is disposed on each pivot between the side of the inverted U-shaped frame and the inner face 5 of the adjacent rail of the ladder. When not in use the balancer attachment may be rocked on its pivot bolts 15 and folded back along the ladder as indicated by dotted lines in Figures 2 and 3.

10 The wall rest comprises a U-shaped frame 17, best shown in Figure 5, to comprise side members 18 and a cross bar 19, the latter having terminal flanges 20 bolted, as shown at 21, or otherwise secured to the side members 18. The side members 18 are offset inwardly, as shown at 21a, to clear the sides of the U-shaped frame 12 and are pivotally secured to the top of the side rails 10 of the ladder through the medium of pivot bolts 22. A spacer 23 is disposed on the pivot bolts 20 between each side member 18 of the wall rail and the inner side of the adjacent rail 10 of the ladder, as best shown in Figure 4.

15 The tip ends of the side members 21 are provided on their upper surfaces with respective 25 grooves 24 to receive the lowermost rung 13 of the inverted U-shaped frame 12, as best shown in Figure 2, and lock the inverted U-shaped frame against collapse, since the weight of the wall rest is greater between the pivot bolts 22 30 and the cross bar 19 than between the pivot bolts and the tip ends of the side members 18. When not in use the wall rest is rocked on its pivot bolts 22 and folded back along the side rails 2 of the ladder as shown by dotted lines in Figure 35

2. In operation, when the inverted U-shaped frame is extended upwardly beyond the ladder and the wall rest tip locked to the frame, the ladder may be set up against the wall and in 40 this position the wall rest spaces the top of the ladder about 10" more or less from the wall 25. The inverted U-shaped frame 12 projects upwardly beyond the ladder and the rungs or rails without may be grasped by the operator to 45 balance himself on the top rung 11 of the ladder while putting up eave troughs and doing other work.

From the above description it is thought that the construction and operation of the invention 50 will be fully understood without further explanation.

What is claimed is:

The combination with a ladder of an inverted U-shaped frame having transverse rungs, pivotal 55

connections between the ends of the frame and the top of the ladder through the medium of which the frame may be extended above the ladder, a frame forming a wall rest pivoted to the upper end of the ladder, said frame having side members extended beyond its pivots and provided with notches adapted to receive one of the

rungs of the inverted U-shaped frame, the weight of the wall rest frame on the opposite side of the pivots therefrom from the notches holding the wall rest frame in position to lock the inverted U-shaped frame in operative position. 5

HENRY SCHWARZ.
